UNITED STATES PATENT OFFICE.

GERTRUDE L. BRYCE, OF SEATTLE, WASHINGTON.

STRAP-FASTENER.

1,287,210.

Specification of Letters Patent. Patented Dec. 10, 1918.

Application filed January 7, 1918. Serial No. 210,600.

To all whom it may concern:

Be it known that I, GERTRUDE L. BRYCE, a citizen of the United States, residing at Seattle, in the county of King and State of Washington, have invented certain new and useful Improvements in Strap-Fastenings, of which the following is a specification.

The object of this invention is to produce an efficient and conveniently regulated strap 10 fastening in the nature of a buckle which is adapted to be employed to adjustably secure the ends of a strap together.

The invention consists in the novel construction of a buckle and in the combination 15 and adaptation therewith of a strap, as will be fully described in the following specification, illustrated in the accompanying drawings, and finally pointed out in the appended claims.

20 In said views, Figure 1 is a front elevational view of a hose supporter to which is applied buckle devices embodying my invention. Fig. 2 is a view in end elevation of the strap and buckle elements of my invention illustrating the manner of operating 25 the same. Fig. 3 is a view similar to Fig. 2 showing the devices in other positions. Figs. 4 and 5 are bottom and top plan views, respectively, of the buckle constituting a part 30 of my invention. Fig. 6 is a detached perspective view of an element of said buckle.

In carrying out my invention I employ a buckle made of wire and comprising a frame member 8 having a tongue-seat 10 and a 35 pair of eyes 11. The tongue member is formed with a looped portion 13, pivot portions 15 extending through the eyes 11, and a pair of parallel tongues 16 directed at right angles to the tongue seat 10.

40 A guard 17 provided for said tongues is formed of sheet metal and consists in a shank 18 having tubular portions 20 formed upon each side for the reception of the tongues 16, and a head 21 extending laterally for approximately the width of a strap S with 45 which the buckle is used, said head being provided with a straight outer edge 22 over which said strap may be stretched, as will be presently explained.

50 Said guard is mounted on said tongues by engaging the tubular portions 20 over the same so that the outer edge 22 of the guard will be positioned inwardly of the tongue seat 10 and have the tongues project beyond 55 the guard sufficiently to penetrate the strap end S¹ to perform their necessary functions.

The other end S² of said strap is secured, as by stitching, to the looped portion 13 of the buckle, and thence extends over the guard 17 about the edge 22 and thence doubling back through the frame member 8, the tongue-points penetrating and protruding through the strap fabric. In this manner the strap end S² is stretched over and covers the tongue member, and is directed 65 outwardly to nearly the end of the tongue-points, hence when the other end S¹ of the strap, after being passed, for example, about an article as A in Figs. 1 and 2, is threaded through the loop of the frame-member, and tension is applied to strap end 70 S¹, the application of such force is made through the strap-end S² at the outer extremity of the tongue member, to be drawn down closely and firmly in contact with the 75 strap-end S¹ where it passes over the tongue-seat 10 and causes the tongue-points to penetrate the strap-end S¹ and hold it in security.

Any pull upon the strap-end S¹, while tending to draw the same through the frame, 80 will draw the tongue-points down more firmly upon the strap, and they will re-engage the strap immediately upon the pull upon the end S¹ being discontinued.

To loosen the strap, the end S¹ is pulled 85 sufficiently to release the tongue-points and the thumb of the operator is pressed upon the rear portion of the buckle, over the loop 13 which causes the tongue-member to rock on its pivotal connections 15 with the eyes 11 90 of the frame member, and remove the tongue-points free from the tongue-seat 10 of the frame member and clear of the strap-end S¹.

In Fig. 1 the buckle is shown applied to a 95 hose supporter and serves to secure the usual hose attachment B at adjusted elevations.

The invention is very simple and inexpensive to manufacture, and will accomplish efficiently the purposes for which intended.

What I claim, is—

1. The combination with a buckle comprising a frame member having a tongue seat, a tongue member pivotally connected to said frame member and formed with a loop element, and a guard formed to provide a 100 head element of approximately the width of the buckle and with a shank element having tubular portions whereby the guard is secured to the tongues of said tongue member, of a strap connected to the buckle by having 105 one of its ends engage said tongues and thence extend over said guard to have the 110

adjacent extremity of the strap permanently fastened to said loop element, the other end of the strap being passed through the opening of the frame member and engaged with the tongues.

2. The combination with a buckle having a frame member having a tongue seat, a tongue member hingedly connected to said frame member, and a guard of substantially 10 a T-shape secured to the tongues of said tongue member, of a strap having one of its ends permanently secured to said tongue member thence passing over said guard to be pierced by said tongues, said guard serving 15 to maintain the strap in proximity to said tongue seat.
3. The combination with a strap, of a

buckle comprising a tongue member having a transverse loop and a pair of integral parallel pointed tongues, a frame member pivotally connected at its opposite ends to said tongue member and affording a tongue seat, and a guard mounted on said tongues, and having adjacent to said tongue seat a straight edge about which the strap may be stretched, 25 the points of said tongues extending beyond the outer extremity of said guard to engage through two thicknesses of the strap.

Signed at Seattle, Washington, this 26th day of December, 1917.

GERTRUDE L. BRYCE.
